BLIND-STITCH MACHINE

Charles W. Mueller, St. Louis, Mo., assignor to
 Lewis Invisible Stitch Machine Company, a
 corporation of Maine

Application July 29, 1943, Serial No. 496,579

15 Claims. (Cl. 112—176)

1 In certain types of blind-stitch sewing machines, particularly the small high speed machines, it has been the common practice to have the node-former carried by the work table. It is necessary that the node-former be yieldable in order to accommodate seams and also be so arranged that it may be withdrawn from the presser foot for the insertion and removal of work. Heretofore, and prior to this invention, it was the common practice to make the entire work table yieldable. Thus, the node-former was mounted upon a yieldable work table as was also the work support which consists of two independently moveable plattens that support the work against the presser foot.

A heavy pressure or force is required to maintain the node-former in position when forming a node through the opening in the presser foot. This force is commonly exerted by a heavy spring which, in the construction mentioned, acts upon the work table. To open the machine for the insertion or removal of work, it is necessary for the operator, manually, and commonly through a knee press, to overcome the resistance of the heavy spring.

An object of this invention is to provide a construction in which the machine may be opened without the necessity of overcoming the resistance of the heavy yieldable force maintaining the node-former in operative position. Another object of the invention is to provide a construction in which the work support may be moved away from the presser foot independently of the node-former. A further object of the invention is to provide a construction in which, by a single manual operation, the work support is moved away from the presser foot and the node-former is positioned away from the presser foot, providing an ample unobstructed opening for the insertion or removal of work.

The foregoing objects, and certain advantages that will hereinafter appear, are realized in the embodiment of the invention illustrated, by way of an example, in the accompanying drawings and described in detail below:

The drawings include:

Fig. 1, which is a plan view of a machine embodying the invention;

Fig. 2, which is a front elevation of the same;

Fig. 3, which is a sectional front elevation of the same taken on the line 3—3 of Fig. 1;

Fig. 4, which is a sectional plan taken on the line 4—4 of Fig. 2;

Figs. 5, 6, 7, 8, 9, 10, and 11, which are transverse sectional elevations taken on the irregular

lines 5—5, 6—6, 7—7, 8—8, 9—9, 10—10, and 11—11, respectively of Fig. 3; and

Figs. 12 and 13, which show in elevation certain parts of the machine in two different positions of their movement.

2 The machine illustrated in the drawings includes a frame upon which all of the mechanism is mounted. This frame comprises a base 1, a post 2 secured to the base at the rear thereof, an arm 3 extending from the upper end of the post, a forwardly extending arm 4, secured to the end of the arm 3, and a work table 5 secured to the base at the front thereof and extending to the arm 4. The various sections of the frame are hollow, and within the sections, operating and driving mechanism is mounted.

The sewing machine is driven through a main shaft 6 that is journaled in the post 2 and the arm 3. This shaft extends through the post and 10 has mounted thereon a combined pulley 7 and hand wheel 8. The pulley is driven through a belt 9 from a power shaft or an electric motor, not shown.

On the end of the arm 4, there is a presser foot 10 which overhangs the end of the work table 5. The work is supported against this presser foot. The presser foot is of the usual and well-known construction and has an opening 11 therethrough, through which, during the operation of 20 the machine, nodes of material operated upon extend.

The stitch-forming mechanism is of the usual and well-known kind in sewing machines of this type. A needle bar shaft 12 is journaled in the arm 4 and extends through the end of the arm. On the extended end of the shaft 12, there is 30 mounted a needle bar 13 which carries a curved needle 14. Through suitable connections with the main shaft, the needle bar shaft is oscillated to cause the needle to move across the opening in the presser foot. The particular machine illustrated is a chain-stitch machine and is provided with a looper 15 which cooperates with the needle in the formation of stitches. The invention, however, is not restricted to a chain-stitch, blind-stitch machine as it is equally applicable to a lock-stitch, blind-stitch machine of the same kind.

The work operated upon, in the region of the 40 stitch line, is supported against the under side of the presser foot by a work support which consists of a pair of work-supporting plattens 16 and 17. These plattens are mounted for independent pivotal movement and for movement toward and 50 away from the presser foot. They are resiliently

urged towards the presser foot. Both are mounted in the same manner. The mounting for the platten 17 (Figs. 10 and 11) includes a lever 18, in the nature of a bell crank lever, that is pivotally mounted on a shaft 19. One arm 18a of the lever is curved, as shown, and on the end thereof, there is formed a boss 18b. A pivot pin 20 is mounted in the boss and extends therefrom. A bracket 17a is formed on the platten 17 is pivotally mounted on the pivot pin 20. Another arm 18c of the lever 18 has secured thereto one end of a spring 21. The other end of the spring 21 is secured in an adjustable anchor pin 22 threaded through an opening in the side wall of the work table 5. A check nut 23 secures the anchor pin in adjusted position. The spring 21 is a comparatively light spring as the function of the plattens is merely to support the portion of the work operated upon against the presser foot.

The end portion of the work table extending under the presser foot is of much greater distance from the presser foot than the work table of the common machine of this kind. The distance between the work table and presser foot is sufficient, when unobstructed, to permit the ready insertion and removal of work between the presser foot and the work table. For the purpose of permitting the ready insertion and removal of work, the plattens are retractable as the work table is fixed. To this end, the lever 18 of the platten 17 is provided with a lug 18d. A like lug is formed on the corresponding lever for the platten 16 which is indicated by the numeral 16'. Underlying these lugs (Figs. 2, 4, 7, 10, and 11), and normally spaced from them, there is a rod 24 which extends from a bushing or collar 25 that is secured to a shaft 26 (Fig. 4). The rod 24 is normally spaced from the lugs to permit limited independent movement of the plattens. Upon rotating the shaft 26, counterclockwise as seen in Figs. 10 and 11, the platten supporting levers, such as the lever 18, are moved to withdraw the plattens to a position away from the presser foot—to the position of the platten 17, shown in Fig. 10.

Rotation of the shaft 26 to withdraw the plattens is effected, manually, through a knee press 27 (Figs. 1 and 2).

The knee press is secured to an offset portion 28a of a rod 28 which is secured through a connector 29 to a rod 30. This rod 30 extends into the base 1 and it is journaled therein. Within the base 1 (Figs. 4, 5, 6, 10, and 11), there is secured to the rod 30 a lever 31. To the end of this lever, there is pivotally secured one end of a link 32, the other end of which is pivotally secured to the end of a lever 33 that is secured on the shaft 26. When the knee press 27 (Figs. 1 and 2) is moved to the right, the rod 30 is rotated counterclockwise. The lever 31 (Figs. 4, 5, and 6) draws the link down and rotates the shaft 26 to withdraw the plattens to their open position, away from the presser foot.

The work-presenting mechanism for presenting work to the needle includes an oscillating node-former 34 of the sector disk type. The node-former (Fig. 4) is mounted on the end of a shaft 35 that is journaled in spaced bearings 36 and 37 of a cradle 38. The cradle 38 is pivotally mounted on centering pins 39 and 40 threaded through brackets 41 and 42 extending inwardly from the side wall of the work table. The cradle 38 (Figs. 3 and 4), and in consequence the node-former 34, is resiliently held in adjusted, operative position by a heavy spring 43. One end of this spring

is secured to a lug 44 extending from the cradle and the other end is secured to an adjustable anchor pin 45 threaded through an opening in the front wall of the work table. The force exerted on the cradle by the spring 43 may be adjusted, to a limited extent, by adjusting the anchor pin 45. The anchor pin 45 is held in adjusted position by a check nut 46.

The node-former is oscillated in timed relation with the stitch-forming and feed mechanism. In the upper position, adjacent the presser foot (Fig. 8), the node-former forces a node of the material operated upon through the opening in the presser foot and into the path of the needle. After the passage of the needle, the node-former is withdrawn (Fig. 9) to a position away from the presser foot. This is effected through oscillation of the shaft 35. When additional material, such for example as seams, pass through, the node-former must yield. It is, thus, yieldingly mounted as above described.

The position of the node-former, in node-forming position, with respect to the presser foot, determines the extent of the node formed and in consequence, the depth of penetration of the needle. In the machine illustrated, the depth of penetration of the needle is adjustable through adjustment of the cradle 38, that is, by limiting the movement of the cradle under the action of the spring 43. For this purpose, the cradle is provided with a depending arm 47. At the end of the arm 47 there is provided a countersunk opening 48, the countersink (Fig. 7) preferably being a sector of a sphere. A screw 49 having a head 50 complementary to the countersink extends through the opening and the shank 51 thereof, which is of lesser diameter than the opening, is threaded into the end of a rod 52. The other end of the rod has a ball-receiving fitting 53 secured thereon which receives a ball fitting 54 secured on a lever 55. The lever 55 is secured on one end of a shaft 56 journaled in a bearing bracket 57. On the other end of the shaft 56, there is secured another lever 57' which is connected through a link 58 to a movable block 59 slidably mounted in the post 2. A threaded rod 60 having a knurled finger wheel 60' thereon engages the block 59 and serves as the medium through which the depth of penetration of the needle is adjusted. Through this medium, the head of the screw 49 is positioned and acts as a stop for the cradle. The cradle is, however, free to yield under a force acting upon the node-former.

The node-former is oscillated through a train of actuating mechanism driven from the main shaft and oscillating the shaft 35. This mechanism includes an eccentric 61 (Fig. 7) mounted on the main shaft and an eccentric strap 62 surrounding the eccentric. An eccentric rod 63, connected to the eccentric strap at one end, is pivotally connected, through a ball and socket joint, at the other end to the end of a lever 64. The lever 64 extends from a bushing 65 rotatably mounted upon a shaft 66 in the base 1. Another lever 67 extends from the bushing 65 and is connected through a ball and socket joint to one end of a connecting rod 68. The other end of the connecting rod 68 is pivotally connected, through a ball and socket joint, to one end of a lever 69. The lever 69 is pivoted between its ends on a pivot shaft 70 that is formed integral with, and eccentric with respect to, a shaft 71 journaled in a transverse bearing bracket 72 in the base 1. The other end of the lever 69 is piv-

totally connected, through a ball and socket joint, to a lever or crank arm 74 on the end of the shaft 35. On rotation of the main shaft, the eccentric oscillates the levers 64 and 67 which, through the connecting rod 68, oscillates the lever 69. Oscillation of the lever 69 is transmitted through the link 73 and the crank arm 74 to the shaft 35. In Fig. 8, the connecting rod 68 is illustrated in one extreme position. In this position of the connecting rod, the node-former 34 is in node forming position. Fig. 9 illustrates the same parts in the opposite position. In this position, the node-former is withdrawn from the presser foot. The link 73, connecting the lever 69 and the crank arm 74, permits the shaft 35 to move, substantially vertically, when it is necessary for the node-former to yield.

From Figs. 8 and 9, it will be apparent that even with the work-supporting plattens withdrawn, the node-former would obstruct the opening and the insertion and removal of work between the presser foot and the plattens. For this reason, in the machine illustrated, the node-former 34 is retracted, when the knee press 27 is actuated to the full extent, to a position (Fig. 10) in which there is a clear opening for the insertion and removal of work.

Manual retraction or withdrawal of the node-former is effected by rotating the shaft 71 and so shifting the pivot 70. For this purpose, a spur gear 75 is secured on the shaft 71. The gear 75 meshes with a gear 76 secured on a shaft 77 that is rotatably mounted in and extends through the bearing bracket 72. The gears 75 and 76 have a ratio of two to one. On the gear 76, and extending from the side thereof, there is a stud 78 which constitutes a crank. This stud 78 is positioned to be engaged by a shoe 79 secured on the link 32.

The normal position of the stud 78 (Fig. 6) is slightly above the horizontal plane passing through the axis of the shaft 71. It is held in this position by a spring 80 (Figs. 4 and 5). On the extended end of the shaft 77, there is secured a block 81 which carries an eccentric pin 82 extending from the side thereof. One end of the spring 80 is secured to this pin and the other end of the spring is secured to a stationary pin 83 extending inwardly from the end wall of the base 1.

The normal position of the shoe 79 (Fig. 6) is out of contact with and spaced above the stud 78. This relation permits a slight withdrawal of the work-supporting plattens 16 and 17 (Fig. 11) before the shoe engages the stud 78. The reason for this is to permit the operator to release the work while the machine is operating. The wide engagement of the plattens and presser foot with the work does not permit the work to be turned in the machines. Heretofore, in machines of this kind, when it was necessary to turn the work, the operator had to stop the machine, open it and then turn the work. By releasing the pressure on the plattens, as above described, the work rides on the node-former and may be turned on the node-former as a pivot.

When the machine is stopped, and the operator presses the knee press the full extent, the shoe 79 engages the stud 78 and rotates the gear 76. The gear 75 and shaft 71 are thus rotated and the pivot pin 70 is shifted. In Fig. 12, the pivot pin 70 and the node-former 34 are shown in their normal position. As the machine is stopped, the lower end of the lever 69 is held by the connecting rod 68. Shifting of the pivot 70 thus causes

movement of the lever about its pivotal connection with the connecting rod 68 and retracts the node-former 34 to the position illustrated in Figs. 10 and 13. Upon release of the knee press, the work-supporting plattens and the node-former return to their normal positions. This is effected through the springs acting on the plattens and the spring 80.

In the machine illustrated, the depth of penetration may be varied. This is effected through the eccentric pivot. The shaft 71 extends through the bearing bracket 72 and has secured thereon a circular block 84. From this block, and through a slot provided therefor in the top of the work table, a finger lever 85 extends. The edge of the block is provided with spaced detent recesses 86 and 87 which cooperate with a resilient detent 88 mounted in a disk sector 89 secured on the shaft 71. By shifting the finger lever from one position to the other, as represented by the detent recesses 86 and 87, the eccentric pivot 70 of the lever 69 is shifted. This changes the extent of oscillation of the node-former and so varies the penetration.

From the foregoing description of the embodiment of the invention illustrated in the drawing, it will be seen that by this invention there is provided an easy opening machine and a machine in which the work may be readily turned while the machine is in operation. To maintain the node-former in position to form a node, a spring force of approximately forty pounds is required. In prior machines, the operator, through the knee press had to overcome this force to open the machine. In the machine of this invention, the operator need only over-balance a force of less than ten pounds to open the machine. By providing movement of the plattens prior to movement of the node-former, through the knee press, the operator uses the one control for turning the work and opening the machine.

In machines of this kind, the adjustment of the node-former is very delicate. Where the node-former is carried by a movable work table, the machine must be adjusted frequently. This is because such machines are opened and closed repeatedly in the course of a day. The closing is effected by a complete release of the knee press which permits the work table to be slammed against the adjustable stop under the force of the heavy spring. In the machine of this invention, the adjustment of the node-former is not disturbed in opening and closing the machine.

It will be obvious that various changes may be made, by those skilled in the art, in the details of the embodiment of the invention illustrated in the drawings and described above, within the principles and scope of the invention as expressed in the appended claims.

I claim:

1. In a blind-stitch sewing machine of the kind described, the combination comprising a presser foot having an opening therethrough, stitch-forming mechanism on one side of the presser foot, work-presenting mechanism for presenting work to the stitch-forming mechanism including a movable node-former movable toward and away from the presser foot, mechanism for effecting movement of the node-former in timed relation with respect to the stitch-forming mechanism, a work support for supporting the work against the presser foot mounted for movement toward and away from the presser foot independently of the node-former, and means for acting upon said mechanism for effecting movement of the node-

former away from the presser foot, and means for moving the work-support away from the presser foot including means for actuating said means for effecting movement of the node-former away from the pressure foot.

2. In a blind-stitch sewing machine of the kind described, the combination comprising a presser foot having an opening therethrough, stitch-forming mechanism on one side of the presser foot, work-presenting mechanism for presenting work to the stitch-forming mechanism including a movable node-former movable toward and away from the presser foot, mechanism for effecting movement of the node-former in timed relation with respect to the stitch-forming mechanism, a work support for supporting the work against the presser foot mounted for movement toward and away from the presser foot independently of the node-former, means for moving the work support away from the presser foot, and means actuated thereby for acting upon said mechanism for effecting movement of the node-former to move the node-former away from the presser foot.

3. In a blind-stitch sewing machine of the kind described, the combination comprising a presser foot having an opening therethrough, stitch-forming mechanism on one side of the presser foot, work-presenting mechanism for presenting work to the stitch-forming mechanism including a movable node-former movable toward and away from the presser foot, mechanism for effecting movement of the node-former in timed relation with respect to the stitch-forming mechanism, a work support for supporting the work against the presser foot mounted for movement toward and away from the presser foot independently of the node-former, means for moving the work support away from the presser foot, and means operative upon movement of the work-support a predetermined distance from the presser foot for acting upon said mechanism for effecting movement of the node-former to move the node-former away from the presser foot.

4. In a blind-stitch sewing machine of the kind described, the combination comprising a presser foot having an opening therethrough, stitch-forming mechanism on one side of the presser foot, work-presenting mechanism for presenting work to the stitch-forming mechanism including a movable node-former movable toward and away from the presser foot, mechanism for effecting movement of the node-former in timed relation with respect to the stitch-forming mechanism including an angularly movable shaft, a work support for supporting the work against the presser foot mounted for movement toward and away from the presser foot, and means for moving the work support away from the presser foot including means for effecting angular movement of the shaft of said mechanism about its axis for effecting movement of the node-former away from the presser foot.

5. In a blind-stitch sewing machine of the kind described, the combination comprising a presser foot having an opening therethrough, stitch-forming mechanism on one side of the presser foot, work-presenting mechanism for presenting work to the stitch-forming mechanism including an angularly movable node-former, a work support for supporting the work against the presser foot mounted for movement toward and away from the presser foot, and means for moving the work support away from the presser foot including means for effecting angular movement of the node-former.

6. In a blind-stitch sewing machine of the kind described, the combination comprising stitch-forming mechanism including a movably mounted needle bar and a needle carried thereby, means for actuating said stitch-forming mechanism, work-presenting mechanism including a movable node-former movable toward and away from the path of the needle, actuating mechanism for the node-former, mechanism interconnecting the actuating means for the stitch-forming mechanism and the node-former actuating mechanism positioning the node-former relative to the needle, and means for effecting actuation of the actuating mechanism independently of said interconnecting mechanism to withdraw the node-former away from the path of the needle.

7. In a blind-stitch sewing machine of the kind described, the combination comprising a presser foot having an opening therethrough, stitch-forming mechanism including a needle on one side of the presser foot, work presenting mechanism for presenting work to the stitch-forming mechanism including an oscillating node-former movable toward and away from the needle, operating mechanism for the node-former, and manually operative means for rotating the node-former about its axis away from the needle.

8. In a blind-stitch sewing machine of the kind described, the combination comprising a presser foot having an opening therethrough, stitch-forming mechanism on one side of the presser foot, work-presenting mechanism for presenting work to the stitch-forming mechanism including a node-former movable between positions adjacent to and away from the needle, means for actuating the node-former in timed relation with respect to the needle, and manually operative means for effecting movement of the node-former independently of and in accordance with the movement effected by said node-former actuating means for moving the node-former to a position away from the needle.

9. In a blind-stitch sewing machine of the kind described, the combination comprising a presser foot having an opening therethrough, stitch-forming mechanism on one side of the presser foot, work-presenting mechanism for presenting work to the stitch-forming mechanism including a node-former movable toward and away from the presser foot, actuating mechanism for the node-former including a rotatably mounted shaft, and manually operative means for rotating the shaft about its axis to move the node-former away from the presser foot.

10. In a blind-stitch sewing machine of the kind described, the combination comprising a presser foot having an opening therethrough, stitch-forming mechanism on one side of the presser foot, work-presenting mechanism for presenting work to the stitch-forming mechanism including an oscillating node-former, oscillatable between a position adjacent the presser foot and a position away from the presser foot, means for oscillating the node-former in timed relation with respect to the stitch-forming mechanism including an angularly movable shaft, and manually operable means for effecting angular movement of the shaft independently of said node-former oscillating means to position the node-former away from the presser foot.

11. In a blind-stitch sewing machine of the kind described, the combination comprising a presser foot having an opening therethrough,

stitch-forming mechanism on one side of the presser foot, work-presenting mechanism for presenting work to the stitch-forming mechanism including an angularly movable node-former, means for effecting movement of the node-former including a shaft, a lever for actuating the shaft and a shiftable pivot for the lever, and manually operative means for shifting the pivot to position the node-former for the insertion and removal of work.

12. In a blind-stitch sewing machine of the kind described, the combination comprising a presser foot having an opening therethrough, stitch-forming mechanism including a needle on one side of the presser foot, means for actuating the stitch-forming mechanism, work-presenting mechanism including an angularly movable node-former for presenting work to the needle, a resilient mounting for the node-former, means for actuating the node-former including a pivoted lever and a shiftable pivot for the lever, and manually operative means for shifting said shiftable pivot to position the node-former for the insertion and removal of work.

13. In a blind-stitch sewing machine of the kind described, the combination comprising a presser foot having an opening therethrough, stitch-forming mechanism including a needle on one side of the presser foot, means for actuating the stitch-forming mechanism, work-presenting mechanism for presenting work to the stitch-forming mechanism including a movable cradle, a shaft journaled in the cradle, resilient means for resiliently positioning the cradle and a node-former mounted on the shaft and positioned upon actuation to project a node of the work into the path of the needle, means for actuating the node-former including a pivoted lever and a shiftable pivot for the lever, and manually operative means for shifting said shiftable pivot to position the node-former for the insertion and removal of work.

14. In a blind-stitch sewing machine of the kind described, the combination comprising a presser foot having an opening therethrough, stitch-forming mechanism including a needle on

one side of the presser foot, means for actuating the stitch-forming mechanism, a work support for supporting the work against the presser foot mounted for movement toward and away from the presser foot, work-presenting mechanism for presenting work to the stitch-forming mechanism including an oscillating node-former oscillatable between a position adjacent the presser foot and a position away from the presser foot, 5 means for oscillating the node-former in timed relation with respect to the stitch-forming mechanism including an angularly movable shaft, and manually operable means for moving the work support away from the presser foot and effecting angular movement of the shaft about its axis to position the node-former for the removal and insertion of work.

15. In a blind-stitch sewing machine of the kind described, the combination comprising a presser foot having an opening therethrough, 10 stitch-forming mechanism on one side of the presser foot, means for actuating the stitch-forming mechanism, a work support for supporting work against the presser foot mounted for movement toward and away from the presser foot, work-presenting mechanism for presenting work to the stitch-forming mechanism including an angularly movable node-former, means for effecting movement of the node-former including a shaft, a lever for actuating the shaft, and a shiftable pivot for the lever, and manually operative means for moving the work support away from the presser foot and for shifting said shiftable pivot to position the node-former for the 15 insertion and removal of work.
